US00D919019S

(12) **United States Design Patent** (10) **Patent No.:** **US D919,019 S**
(45) **Date of Patent:** **** May 11, 2021**

(54) **EXERCISE APPARATUS**

- (71) Applicant: **Jaquish Biomedical Corporation**,
Nevada City, CA (US)
- (72) Inventors: **John Paul Jaquish**, Nevada City, CA
(US); **Paul Edward Jaquish**, Nevada
City, CA (US); **Henry David Alkire**,
Nevada City, CA (US)
- (73) Assignee: **Jaquish Biomedical Corporation**,
Nevada City, CA (US)
- (**) Term: **15 Years**
- (21) Appl. No.: **29/730,874**
- (22) Filed: **Apr. 9, 2020**

Related U.S. Application Data

- (63) Continuation of application No. 29/681,204, filed on
Feb. 22, 2019.
- (51) **LOC (13) Cl.** **21-02**
- (52) **U.S. Cl.**
USPC **D21/679**
- (58) **Field of Classification Search**

(57) **CLAIM**

The ornamental design for an exercise apparatus, as shown and described.

DESCRIPTION

FIG. 1 is a perspective view of an exercise apparatus showing our new design;

FIG. 2 is a front view, back view is a mirror image thereof;

FIG. 3 is a top view thereof;

FIG. 4 is a bottom view thereof; and,

FIG. 5 is a side view, the opposite side is a mirror image thereof.

The broken lines shown in the figures are for the purposes of illustrating portions of the exercise apparatus which form no part of the claimed design.

1 Claim, 5 Drawing Sheets
